UNITED STATES PATENT OFFICE.

FRANKLIN C. NICKEL, OF CONCORD, ILLINOIS, ASSIGNOR TO MONMOUTH ACETYLENE-ELECTRIC MANUFACTURING COMPANY, OF MONMOUTH, ILLINOIS, A CORPORATION OF ILLINOIS.

ACETYLENE-GAS GENERATOR.

No. 901,640.

Specification of Letters Patent.

Patented Oct. 20, 1908.

Application filed February 13, 1908. Serial No. 415,634.

To all whom it may concern:

Be it known that I, FRANKLIN C. NICKEL, a citizen of the United States, residing at Concord, in the county of Morgan and State 5 of Illinois, have invented a new and useful Improvement in Acetylene-Gas Generators, of which the following is a specification.

My invention relates to an improvement in the class of gasometer-apparatus for generating gas from calcium-carbid by feeding the latter automatically to the water-containing generating-chamber of the apparatus. Such a generator forms the subject 10 of Letters Patent No. 795,478, dated July 15, 25, 1905.

The primary object of my invention is to provide novel and effective means for automatically taking care of the condensation from the generated gas in the apparatus and 20 of the pressure and volume relief of the apparatus.

In the accompanying drawing, Figure 1 is a view in vertical sectional elevation of an acetylene-gas generator containing my improvements, and Fig. 2, a broken section on line 2, Fig. 1.

The apparatus shown to be provided with my improvements involves, as its general construction, that illustrated and described 30 in the aforesaid patent, though it is not intended to limit my present invention thereto.

The reservoir 3 for containing the sealing water, the level of which is indicated at 4, is provided in its lower part with a crown-like false bottom 5 forming in the base-portion of the reservoir the generating-chamber 6 containing water, the level of which is indicated at 7. The outlet-pipe 8 for the generated gas rises from the generating chamber, and the gas-discharge pipe 9 extends parallel therewith to receive into its upper end the gas which flows from the corresponding end of the pipe 8 into the gas-space in the upper part of the gasometer-forming bell 10, which works in the reservoir 3 in a usual manner. The pipe 9 has coupled to its lower end an extension 9¹ projecting at a right-angle from it through the wall of the reservoir, beyond which there 45 rises from its end a pipe 11, which passes centrally through the purifier 12 consisting of a closed cylinder filled with cotton-felt 13, or other suitable purifying medium.

The pipe in the purifier contains perforations at 14 in its lower end and similar perforations 15 in its upper end, with a plug 16 between its ends to direct the gas from the pipe 9 by way of perforations 14 through the medium 13 and effect therein its purification and return the purified gas through 60 the perforations 15 into the pipe 11, which connects beyond the upper end of the purifier with the service-pipe 17 at a shut-off valve 18.

The means provided for automatically 65 supplying the calcium-carbid in proper proportions to the generator 6 may be the same as are illustrated and described in the aforesaid patent and need not, therefore, be shown in all details in the present drawing, which 70 presents thereof, by way of identification, only the tubular member 19 communicating at its lower end through the false bottom 5 with the generating chamber, the inverted cup-like member 20, the U-shaped vertically 75 movable bar 21, one upper end of which (not shown) is connected with the device for controlling the feed of calcium-carbid from its container (also not shown) into the member 19, and its other upper end in engagement with a lever 22 having one end fulcrumed at 23 and its opposite end linked to the top of the bell 10.

The parts thus far described present no 85 important features of novelty.

At one side of the generating-chamber 6 is supporting on its wall an external condensation-chamber 24 extending upwardly beyond the water-level 7 and provided thereat with an overflow 24¹, the top of this chamber being open to permit free access to it for cleaning and other purposes. A relatively narrower extension 25 of the condensation-chamber 24, freely communicating therewith through an opening 26 in the wall of the 95 generating-chamber and affording a supplemental condensation-chamber, is supported on the inner side of said wall to reach upwardly to the water-level at 7. A branch-pipe 27 depends from the extension 9¹ into the chamber 24 to take from the purifier 12 the water of condensation that accumulates in the latter and which, if left therein, would tend to impair the gas; and any water of condensation in the pipe 9 also drains off 100 through the branch 27. A blow-off pipe 28

extends vertically in the bell 10, passing through its upper closed end to discharge to the atmosphere and extending at its lower end through the false bottom 5, below which it terminates in the chamber-section 25 in an expanded tubular head 29 serrated to afford opening-producing teeth 30 about its open lower end. A branch 31 of the escape-pipe 28 communicates therewith above the false bottom and rises to extend parallel with the pipes 8 and 9 in a guide-sleeve 32 depending centrally in the bell 10 and containing at a proper height above its open lower end, perforations 33.

15 The gas generated from calcium-carbid fed into the water contained in the chamber 6, as in the manner set forth in said patent, and which accumulates in the space above the water-level 7, finds its outlet through the pipe 8 into the space above the water-level in the gasometer 10, which is supported, as usual, by the pressure of the gas in it, to produce by its weight the pressure for the service. From the gasometer the gas discharges through the pipe 9 to the service-pipe 17 through the purifier 12, whence the water of condensation discharges into the chamber 24. In the event of the apparatus generating an excess in volume of the gas, 20 when the resultant accumulation in the gasometer raises the bell 10 sufficiently to elevate the perforations 33 in the guide-sleeve 32 above the water-level at 4, the surplus gas will have access to those perforations and 25 pass into the upper end of the pipe 31 to be carried by it to the blow-off pipe 28, which conducts it to the atmosphere. In the event of the apparatus generating an excessive pressure of gas in the chamber 6 the excess 30 of pressure, acting against the surface of the water in that chamber, will lower its level in the chamber 25 to the serrations 30, the overflow 24¹ taking care of the excess of water thereby introduced into the chamber 24; and 35 because the depression of the level in the chamber-section 25 opens communication, at the serrations 30, between the generating-chamber and the interior of the head 29, the excess of pressure will be relieved through 40 the pipe 28 to escape into the atmosphere. All accumulation of water of condensation in the pipes 28 and 31, which would tend to obstruct those pipes, is prevented by their draining into the condensation-chamber.

50 55 What I claim as new and desire to secure by Letters Patent is—

1. In an acetylene-gas generator, the combination with the reservoir containing the generating-chamber in its base-portion and the gasometer into which rises the outlet-pipe from said chamber, of a condensation-chamber having an external section on the outer wall of the generating-chamber and a relatively smaller internal section on the inner wall thereof, said sections intercommuni-

cating and the inner section being open to the generating-chamber, a discharge-pipe for the service-gas leading from the gasometer and communicating with said external section, and a pressure-relief pipe dipping into 70 said inner section and leading therefrom to the atmosphere.

2. In an acetylene-gas generator, the combination with the reservoir containing the generating-chamber in its base-portion and the gasometer into which rises the outlet-pipe from said chamber, of a purifier having a service-pipe extending from it, a condensation-chamber having an external section on the outer wall of the generating-chamber and 80 a relatively smaller internal section on the inner wall thereof, said sections intercommunicating and the inner section being open to the generating-chamber, a discharge - pipe for the service-gas leading from the gasometer to said purifier and having a branch extending into said external section, and a pressure-relief pipe dipping into said inner section and leading therefrom into the atmosphere. 90

3. In an acetylene-gas generator, the combination with the reservoir containing the generator-chamber in its base-portion and the gasometer into which rises the outlet-pipe from said chamber, of a condensation-chamber having an external section on the outer wall of the generating-chamber and provided with an overflow, and a relatively smaller internal section communicating with 95 said external section and open to the generating-chamber, a discharge-pipe for the service-gas leading from the gasometer, and a pressure-relief pipe dipping into said inner section and leading therefrom to the atmosphere. 100

4. In an acetylene-gas generator, the combination with the reservoir containing the generator-chamber in its base-portion and the gasometer into which rises the outlet-pipe from said chamber, of a condensation-chamber having an external section on the outer wall of the generating-chamber and provided with an overflow, and a relatively smaller internal section communicating with 110 said external section and open to the generating-chamber, a discharge-pipe for the service-gas leading from the gasometer, and a pressure-relief pipe terminating at its lower end in said internal section in a serrated tubular head and leading at its opposite end to the atmosphere. 115

5. In an acetylene-gas generator, the combination with the reservoir containing the generating-chamber in its base-portion and the gasometer into which rises the outlet-pipe from said chamber, of an apertured guide-sleeve depending in the gasometer-bell, a discharge-pipe for the service-gas leading from said gasometer, a condensation-chamber having an open external section on the 125 130

outer wall of the generating-chamber and provided with an overflow, and a relatively smaller internal section communicating with said external section and open to the generating-chamber, a pressure-relief pipe dipping into said inner section and leading therefrom to the atmosphere, and a volume-

relief pipe extending in said sleeve and communicating with said pressure-relief pipe.

FRANKLIN C. NICKEL.
